CARRYING MEANS

Herbert M. Piker, Hamilton, Ohio, assignor to
The Hamilton Metal Products Company, Ham-
ilton, Ohio, a corporation of Ohio

Application July 22, 1940, Serial No. 346,774

1 Claim. (Cl. 16—115)

This invention relates to improvements in carrying means particularly to the handles applied to boxes, lunch kits, and the like and the means for attaching same.

In the manufacture of lunch kits, tackle boxes, display cases and the like, efforts are constantly being made to reduce the manufacturing cost, the number of parts going into those assembled items and the form and configuration of the parts in order to meet competition. One of the chief problems in the manufacture of these and a number of other items is the carrying handle which must be inexpensive in itself and at the same time comfortable in the hand of the user when in use.

One of the chief objects of this invention is, therefore, the provision of an inexpensive handle for a lunch kit or box, a tackle box, utility box and the like, which is inexpensive to manufacture and readily attachable.

Another object of this invention is the provision of means for easily attaching a handle to a box or the like, which is formed of metal, and in which a minimum number of parts are employed.

A still further object of this invention is the provision of a handle including means for co-operating with means supplied by the box with which it is to be used for readily attaching the handle to the box.

It is also an object of this invention to provide a handle formed of a stamping from sheet metal or a casting and in which the handle is complete in itself after said stamping and forming operation and said casting without requiring any further machine operations in order that the handle may be attached to its box.

A still further and specific object of this invention is the provision of a one piece handle readily formed from a sheet metal blank, which when formed includes the body portion of the handle together with means for hingedly attaching same to a box or the like for hingedly arranging the handle in inoperative as well as operative positions on said box.

Other objects and advantages of the present invention should be readily apparent by reference to the following specification considered in conjunction with the accompanying drawings forming a part thereof and it is to be understood that any modification may be made in the exact structural details there shown and described, within the scope of the appended claims, without departing from or exceeding the spirit of the invention.

In the drawings:

Fig. 1 is a front elevation of a lunch kit or box embodying the improvements of this invention.

Fig. 2 is a side elevation of the lunch box as seen in Fig. 1.

Fig. 3 is a top plan view of the lunch box of Fig. 1.

Fig. 4 is a fragmentary elevational view of the handle of this invention attached to the lunch box with the handle in its carrying position as distinguished from the rest position shown in Fig. 1.

Fig. 5 is an enlarged fragmentary sectional view taken on line 5—5 on Fig. 3.

Fig. 6 is a bottom plan view of the handle, per se, as seen from line 6—6 on Fig. 4.

Figs. 7 and 8 are respectively enlarged cross sectional views through the handle taken on lines 7—7 and 8—8 on Fig. 6.

Fig. 9 is an elevational view of a handle modified in construction over that in Fig. 1.

Figs. 10, 11 and 12 are respectively cross sectional views through the handle on Fig. 9 and taken on lines 10—10, 11—11 and 12—12 on said Fig. 9.

Fig. 13 is an elevational view similar to Fig. 9 showing a further modification of the handle.

Fig. 14 is a cross sectional view taken on line 14—14 on Fig. 13.

Fig. 15 is an elevational view of a further modification in the handle, per se, and illustrating the handle in part in final assembly and in part in the act of being finally formed.

Fig. 16 is a cross sectional view similar to Fig. 14 taken on line 16—16 on Fig. 15.

Throughout the several views of the drawings similar reference characters are employed to denote the same or similar parts.

The invention is shown in the drawings in connection with and as applied to a lunch kit or lunch box such as shown in detail in applicant's copending application Serial No. 295,791, filed September 20, 1939, but it is to be understood that the handle and the method of attaching same has equal application to other type of boxes such as tackle boxes, utility boxes, and the like. In each of these boxes use is made of a box proper to which is attached a lid or cover which in turn has secured to it the handle and each of these boxes is formed or stamped from sheet metal and

any reference in this specification to specific parts of the illustrated lunch box parts is to be interpreted as meaning the equivalent part in other types of boxes or chests.

Specifically referring to the drawings the lunch box there illustrated comprises a box proper 20

having the usual bottom, front, back and sides, the upper ends of which are slightly inwardly disposed to be received within the confines of a cover or lid 21. The box proper and the cover are hingedly connected to one another usually along the top edge of the box back as at 22. In order to hold the cover in a closed position use is made of a latch 23 operable by a push button 24 to disengage same from a slot 25 or other latch co-operating part on the cover 21.

The cover 21 has a relatively flat top portion 26 and is provided with a pair of piercings for providing transversely disposed channels or eyes 27 and 28. Disposed within each of said channels or eyes is one end of a coupling or link 29 and 30 which have their other ends connected with the handle proper, indicated in general by the reference numeral 31.

The coupling or links 29 and 30 are identical in construction and each is formed of a length of wire, the ends of which are bent toward one another as at 32 and 33. Extending from the said ends are arms 34 and 35 connected to one another by a cross bar 36.

The handle proper, 31, is formed of a sheet metal blank into a substantially tubular cross section for the greater portion of its length as shown clearly in Fig. 7 and thereby providing the body portion with a top 37, sides 38 and 39 and a bottom 40. The bottom 40 is formed by the longitudinal sides of the blank which are brought into abutment as at 41. The ends of the body portion are let open as at 42 and 43 with these open ends providing in effect depending arms 44 and 45 which as is clearly illustrated in Fig. 1, depend below the body portion of the handle and rest on the top 26 of the cover to provide a space 46 between the handle body portion and cover top 26. When the blank, from which the handle is formed, is stamped out, the portions forming the arms 44 and 45 are simultaneously apertured as at 47 and 48 and which apertures are in alignment with one another upon final formation of the handle. It is through the aligned apertures 47 and 48 that the cross bar 36 of the couplings or links 29 pass in attaching the handle to the box cover 21.

It is believed the operation of this handle is obvious from the disclosure, particularly from Figs. 1 and 4, the former of which illustrated the handle in the normal position of resting on top of the cover and with a space 46 therebelow into which the fingers of the user is inserted for raising the handle to the position of Fig. 4. With the handle in the position of Fig. 1 the couplings or links 29 and 30 are at the inner ends of the elongated apertures 47 and 48 while when the handle is in the raised carrying position of Fig. 4 said couplings or links are at the outer ends of said apertures. The apertures, links and the channels are so co-related to one another that the handle is at all times parallel with the box for maintaining the box in this parallel position when being carried.

The modified handle shown in Figs. 9 to 12, inclusive, and indicated by the reference numeral 59 instead of being folded or formed from a blank of sheet metal, is a casting or solid cross section. With this type of handle the under surface may very readily be undulated so that the said surface conforms with the contour of the hand when holding the handle. These undulations are provided by alternate high spots or portions 51 and low spots or portions 52 and so arranged that the high portions fall between the fingers of the hand

while the low portions coincide with the tops of the fingers.

The handle 50 beyond the undulated body portion is provided with end depending portions 53 and 54 which correspond with the sides 44 and 45 of the handle above described and serves the same purpose of normally supporting the handle on the box cover. These end portions 53 and 54 are also provided with cast elongated apertures 55 and 56 for the coupling and links 28 and 29.

The modification of the handle in Figs. 13 and 14 is formed of a blank of flat sheet metal substantially no wider than the width of the handle and only a trifle longer than the effective length of such handle. This handle 57, similar to handle 50, is stamped to provide an undulated under surface to conform to the contour of the fingers of the hand when carrying the box. In order to provide means for attaching the handle 57 to the box, each end of the handle is bent on itself and thereby provides an elongated aperture 58 having a base 59 and an inner wall 60. The base 59 serves the function of the ends 53 and 54 of the handle 50 and the arms 44 and 45 of the handle 31.

The attachment of the handle 57 to the box is the same as the attachment of the handle 31 namely by way of coupling or links 29 and 30 whose cross bars 36 extend through the apertures 58.

The modified handle of Figs. 15 and 16 indicated by the reference numeral 61 is similar to handle 31 in so far as it is formed of a sheet metal stamping and folded to provide a body portion of tubular cross section. The portion of the handle 61 at the ends of the body portion, however, instead of being formed into arms 44 and 45 are cut short and the ends of the body portion extended as a flat leaf 62. The inner ends of the leaves 62 are formed as ledges 63 for underlying the portions of the handle adjacent thereto as illustrated in the left hand end of Fig. 15. This leaf 62 when in final position forms the base 64 of elongated aperture 65 whose upper edge is defined by cutting short the arms 44 and 45. At the same time the base 64 acts similar to the base 59 of Fig. 13 and the arms 44 and 45 of Fig. 8 in providing a rest or support for the handle 61 on the top 26 of the cover 21.

From the foregoing it will be noted that each of the handles illustrated in this application is formed complete in itself in one stamping and forming operation or else is formed complete in a single casting operation. In the form of handle illustrated in Figs. 1 to 8 inclusive, the stamping die or blanking die must at the same time pierce the arms 44 and 45 in order to provide the coupling attachment means in the handle itself. In the other sheet metal handles illustrated respectively in Figs. 13 to 15 no piercings are required but merely a little additional material at the ends of the body portion of the handle and this additional material then folded, in the same operation as the other folding takes place, onto the body portion to provide the elongated coupling attaching apertures.

From the foregoing it will be also noted that the handle and its attaching means has been reduced to the fewest number of parts, namely, the handle itself and two coupling or link members together with the cover of the box. In this connection it must be noted that the box cover when being formed or when it is blanked out is simultaneously pierced to provide the channels or eyes 27 and 28 with which is used the simplest form

of links or couplings, the open ends of which are received in the cover channels or eyes and the closed ends in the handle apertures.

What is claimed is:

In a carrying handle of the class described formed from a blank of sheet metal having elongated apertures for attaching links adjacent the corners thereof bent to form a handle body portion and end supports, in which the metal is bent to form side portions and a connecting top portion for the handle body portion and end sup-

ports, each said side portion between the end supports being bent toward the other to form a bottom member for the body portion of the handle and with each side of the end supports depending below the handle body portion in the form of arms for rests for the carrying handle, and with the elongated apertures for attaching links in alignment with one another having their major axes extending toward the middle of the handle.

HERBERT M. PIKER.
